UNITED STATES PATENT OFFICE.

CARL A. CARLSON AND KNUTE E. CARLSON, OF CAMPELLO, MASSACHUSETTS.

APPARATUS FOR MOISTENING TOE-PIECES OF SHOES.

1,130,374.

Specification of Letters Patent. Patented Mar. 2, 1915.

Application filed March 20, 1911. Serial No. 615,718.

To all whom it may concern:

Be it known that we, CARL A. CARLSON, a subject of the King of Sweden, and KNUTE E. CARLSON, a citizen of the United States, and both residing in Campello, county of Plymouth, and State of Massachusetts, have invented an Improvement in Apparatus for Moistening Toe-Pieces of Shoes, of which the following description, in connection with the accompanying drawings, is a specification, like letters on the drawings representing like parts.

This invention relates to a novel apparatus for moistening the toe piece or toe cap of a boot or shoe preparatory to lasting the same, whereby the toe piece or cap is put into condition for effectively applying the same in a smooth condition to the toe of the last in a minimum time and with a minimum labor. To this end we employ an apparatus comprising a box, preferably of metal and provide it with a porous diaphragm or partition which separates the box into two chambers, into one of which steam under a predetermined pressure is admitted, and from which the steam passes through the porous diaphragm into the second chamber which is open to the atmosphere and into which the toe piece or cap of the boot or shoe is extended, so as to be moistened by the vapor of steam at atmospheric pressure and in a quiescent state, whereby the toe piece or cap is effectively moistened without danger of burning the leather and with a minimum quantity of steam. For the best results the pressure of the steam admitted into the live steam chamber is not allowed to exceed approximately five pounds. These and other features of this invention will be pointed out in the claims at the end of this specification.

Figure 1 is a front elevation of one construction of apparatus embodying this invention. Fig. 2, a side elevation of the apparatus shown in Fig. 1 with the shoe rest in its folded up position ready for shipment. Fig. 3, a plan view of the apparatus shown in Fig. 1 with the cover or top portion of the apparatus removed. Fig. 4, a vertical section on the line 4-4, Fig. 1. Fig. 5, a vertical section on the line 5-5, Fig. 3, with the cover on, and Fig. 6, a detail to be referred to.

The apparatus herein shown as embodying this invention consists of a substantially rectangular sheet metal box *a* provided with

a removable top or cover *b*. The box *a* is provided in its front face or side with one or more openings *c*, herein shown as two in number, which are located near the upper end of the box below the cover thereof. The openings *c* are made of substantially the shape of a shoe *d* at the toe portion thereof, so that the toe piece *e* of the shoe indicated by dotted lines in Fig. 4 can be inserted therein. Each opening *c* is provided with a substantially wide collar or metal frame 10 having a smooth inner surface to avoid injury to the toe piece by contact therewith. The box *a* is provided within it with a porous partition wall or diaphragm, which is formed as herein represented, by a metal frame or box 12 open at one side and provided with a grating 13 of wire of substantially coarse mesh, upon which rests a substantially thick layer 14 of cotton waste or other fibrous material, which separates the box *a* into two chambers 15, 16.

The chamber 15 may be designated the live steam chamber and is provided as herein shown with a steam supply pipe 17, which is shown as extended across the chamber through the end walls thereof and is provided with perforations 18 in its bottom. The pipe 17 is designed to be connected at one end with a boiler or other source of supply and at its other end with a return pipe to the hot well or other receptacle in a manner well understood, which connections are not herein shown as they are not necessary for a proper understanding of the invention.

The chamber 15 is also provided with a water outlet pipe 20 in its bottom, which is extended up into the chamber 15 a sufficient distance to permit water of condensation to accumulate in the said chamber, so as to insure the steam being of the desired humidity. The water outlet pipe 20 in practice may be connected with any suitable receptacle (not shown). The steam chamber 16 is supplied with vapor from the chamber 15, the fibrous diaphragm or wall 14 being saturated with vapor which rises in the chamber 16 and acts on the toe piece *e* of the shoe *d* to moisten the same and render it pliable. The vapor in the chamber 16 rises therein and finds an outlet through the pipe 25 leading from the removable cover *b* of the box *a*.

The cover *b* may and preferably will be provided with inclined sides 27, which extend

downwardly from the central portion of the cover to the opposite sides thereof, so that water of condensation will flow down the inclined portions of the top of the cover and be conducted to the end walls of the box *a* beyond the openings *c* in the latter, so as to prevent damage to the shoe by water dropping thereon. The shoe is further safe-guarded from the water of condensation by forming a channel or groove 30 on the upper wall of the opening *c*, which may be accomplished by soldering or otherwise securing a metal strip 31 to the top wall of the frame 10.

Provision is made for supporting the boot or shoe while undergoing treatment, and to this end we have provided the rest herein shown, which is made as a wire frame bent at its ends to form journals 32, which are mounted to turn in bearings 33 attached to the front side of the box *a*, said wire being bent to form a frame provided with cross bars 34 in proximity to the openings *c* and with openings 35, (see Fig. 3) opposite said cross bars, for the insertion of the upper of the shoe in its normal condition represented by dotted lines in Fig. 4.

The outer portion of the supporting frame has pivotally connected with it supporting rods or braces 36, which are provided at their free or lower ends with fingers 37, which are designed to enter socket pieces 38 attached to the front side of the box *a*. The supporting frame is pivoted to the box *a* above the bottom of the openings *c*, so that the cross bars 34 are located above the bottoms of said openings, to enable the toe piece of the shoe to be inserted through the opening without touching the walls of the same, and thereby avoid damaging the toe piece.

By providing the supporting frame with the openings 35 at the front end thereof, the toe piece of the shoe is adapted to be inserted into the opening *c* with the upper hanging down in its natural condition, and said shoe can be quickly drawn off of the support in a straight path without interference by the hooks or buttons thereon.

In operating, the steam at a maximum pressure of about five pounds is supplied to the pipe 17 and passes through the perforations thereof into the chamber 15, wherein it comes in contact with the porous diaphragm or wall 14 and saturates the same with moisture, which is vaporized by the heat of the chamber 15 and ascends into the chamber 16, wherein it comes in contact with the toe piece or cap *e* of the shoe *d* and moistens the same, thereby putting the said toe piece in a pliable condition, which enables it to be wiped over the toe of the last quickly and easily and so as to fit smoothly thereon. The surplus vapor may pass out through the upper pipe 25 and be led to a suitable well or receptacle. Water of con-

densate which is found on the upper surface of the cover is deflected to the sides of the chamber 16, and any water of condensation which accumulates on the top wall of the opening *c* flows through the channel or groove 30 to one or both sides of the opening *c* and beyond the same, from which the water drops down upon the fibrous partition.

The pressure of the steam admitted into the chamber 15 is maintained at a low point, preferably not to exceed five pounds, whereby the heat to which the leather is subjected is kept low and burning of the leather is avoided.

When the apparatus is to be shipped, the braces 36 may be removed from their socket pieces 38, and the supporting frame for the shoe may be turned down against the front side of the box *a* and the braces turned up against the front face of the box as represented in Fig. 2.

Claims:

1. In an apparatus of the character described, in combination, a metal box provided with a removable cover having inclined portions extended toward the sides of the box, and having in one face an opening for the insertion of the toe portion of a shoe, a porous diaphragm or partition wall within said box below said opening separating said box into chambers, a steam pipe extended through the lower chamber and provided with a perforation for the passage of steam into said lower chamber, a water outlet pipe for said lower chamber having its mouth above the bottom of the latter, a collar for said opening, and a supporting frame for the shoe secured to the said box in front of said opening and open at its front end to permit the shoe to be inserted into and withdrawn from the opening in the box in a substantially straight path, substantially as described.

2. In an apparatus of the character described, in combination, a metal box provided with a removable cover having inclined portions extended toward the sides of the box, and having in one face an opening for the insertion of the toe portion of a shoe, a porous diaphragm or partition wall within said box below said opening separating said box into chambers, means for supplying steam under pressure to the lower of said chambers, an outlet for water of condensation from said lower chamber, and a support for the shoe in line with the opening in the box, substantially as described.

3. In an apparatus of the character described, in combination, a box provided with an opening in one of its vertical faces for the insertion of the toe portion of a shoe, a partition wall in said box below said opening forming chambers in communication with each other, and a steam inlet

- pipe extended through the lower part of said box and provided within the box with an inlet port for said lower chamber, substantially as described.
- 6 4. In an apparatus of the character described, in combination, a box provided with an opening in one face for the insertion of the toe portion of a shoe, a deflector above said opening, and a support for said shoe in line with said opening, substantially as described.
- 10 5. In an apparatus of the character described, in combination, a metal box provided with an opening in one of its vertical faces and having a removable cover provided with inclined portions, a porous partition wall within the box below said opening separating the box into chambers, and a steam inlet for the chamber below the said partition, substantially as described.
- 15 6. In an apparatus of the character described, in combination, a box provided with an opening in one of its vertical faces for the insertion of the toe portion of a shoe and having a removable cover provided with inclined portions forming deflectors for water of condensation, a porous partition in said box below said opening and forming chambers therein, and means for supplying the lower chamber with steam, substantially as described.
- 20 7. An apparatus of the character described comprising a receptacle having one or more apertures for the reception of a part of a shoe, means for causing hot vapors to circulate within said receptacle, and means for preventing the condensed vapors from coming into contact with the parts of the shoe in the receptacle.
- 25 8. An apparatus of the character described comprising a receptacle having one or more apertures for the reception of a part of a shoe, means for supporting a shoe with a part thereof in the receptacle, and means for causing hot vapors to circulate about the part of the shoe within the receptacle, said receptacle having provision for guiding the condensed vapors that collect on its walls away from the position occupied by the shoe.
- 30 9. An apparatus of the character described comprising a receptacle having one or more apertures for the reception of the toe of a shoe, means for causing hot vapors to circulate within said receptacle, and ribs provided on the walls of said receptacle to deflect moisture collecting on the walls thereof away from said apertures.
- 35 10. An apparatus of the character described comprising a receptacle having a plurality of apertures in one wall thereof for the reception of the toe of a shoe and having a dome-shaped top, an exhaust pipe opening into the top, means for causing hot vapors to circulate within said receptacle, and inclined ribs on the wall of the receptacle positioned to catch the condensed vapor descending from the exhaust pipe and to conduct it away from the position occupied by the shoe.
- 40 70 In testimony whereof, we have signed our names to this specification in the presence of two subscribing witnesses.
